UNITED STATES PATENT OFFICE.

LOUIS STEINBERGER AND GUY HILL, OF BROOKLYN, NEW YORK.

INSULATED SUPPORT FOR ELECTRICAL CONDUCTORS.

1,342,305.

Specification of Letters Patent.

Patented June 1, 1920.

Application filed November 15, 1917. Serial No. 202,114.

To all whom it may concern:

Be it known that we, LOUIS STEINBERGER and GUY HILL, citizens of the United States, and residents, respectively, of the borough of Brooklyn, county of Kings, city and State of New York, have jointly invented certain new and useful Improvements in Insulated Supports for Electrical Conductors, of which the following is a specification.

Our invention relates particularly to insulated supports for mounting inductance coils in radio apparatus.

One of the objects of our invention is to provide a mounting for the inductance coil which is constructed entirely of insulating material, but at the same time so constructed that the insulating studs or posts may be readily and easily fitted into place upon the main support, and also readily and easily removed from their normal position.

Other objects will appear hereinafter from the specification and claims.

Referring to the drawings, in which similar characters indicate the same parts in the several views:

Figure 1 is a plan view of one form of an insulated support embodying our invention, one-half of the support being broken away.

Fig. 2 is a plan view of an insulated support of another form embodying our invention, one-half of which is also broken away.

Fig. 3 is a section partly broken away on line 3—3 of Fig. 1.

Fig. 4 is a section partly broken away on line 4—4 of Fig. 2.

The invention herein shown and described may be applied to any convenient form of support, and we have chosen as illustrative of the supports one form shown in Fig. 1 which is substantially similar to the support described in the application executed by us of even date for a patent on "insulated supports for electrical conductors," and another specific form shown in Fig. 2.

The insulating material used in the construction of this invention may be of any suitable material of that nature, but we prefer to use the insulating material which is known in the art as "electrose."

Referring to Fig. 1 of the drawings, 20 is a disk or plate of solid electrose. 24 are projecting studs extending radially along

the upper surface of the disk or plate. 22 is another series of studs of different shape or construction also projecting from the upper surface of the plate. 50 is the inductance coil which is preferably of ribbon shape, which is coiled into a spiral, and the edge of the said coil is securely held in slots in the upper ends of the studs or pins as will be more particularly hereinafter referred to.

Referring to Fig. 2, the insulated mounting is in general, in the form of a wheel. The central or "hub" portion 10 is secured to the outer or "felly" portion 11, by a series of radially arranged rods or "spoke" portions 12. The outer ring or "felly" portion 11 is constructed of any suitable insulating material which is mechanically strong. The central or "hub" portion may also be made of the same material. The "spoke" portions 12 are secured to the central portion by suitable screws 13 made preferably of insulating material, the respective ends of the "spoke" portions being secured to the "hub" and to the inner surface of the "felly."

The "spoke" portions 12 may be either solid bars or plates of insulating material, or may be hollow tubes, which may be made of any suitable insulating material.

The particular structure which we desire to claim in this application consists in an insulating support and removable pins or studs of insulating material secured to the support, upon which is mounted the inductance coil 50.

Referring more particularly to Fig. 3, we provide suitable holes 25 which preferably extend through the plate or support. The hole 25 is adapted to receive and have secured by a driving fit therein a shank 27 of a pin 28 of insulating material, the upper or head portion extending out over the hole at 29. As a means for easily removing or adjusting the portion of the pin 28 we may provide a hole 26 extending from the lower surface of the insulated plate to the bottom of the hole 25 for the purpose of providing a means by which a tool may be inserted to drive the plug out of the socket 25, or adjust its position therein.

In the form shown in section in Fig. 4 the stud is so shaped that it fits tightly through a hole 33 in the surface of the hollow tube 110 as by a force fit and is provided with a tenon 34 so as to fit in a hole 35 of small

diameter to securely hold the supporting stud in place.

The kerfs or slots 36 are formed in the upper or projecting ends of the supporting studs and the coil 50 is tightly fitted in these kerfs, pins 60 being driven through the projecting ends of the studs so that they pass through holes provided for that purpose in the lower edge of the inductance coil to hold the coil securely in place.

As changes of construction could be made within the scope of our invention, it is intended that all matter contained in the above description or shown in the accompanying drawings shall be interpreted as illustrative and not in a limiting sense.

Having now described our invention, what we claim as new and desire to secure by Letters Patent is:

- 20 1. In a device of the kind described, a support of insulating material having a series of smooth-walled apertures formed therein, a series of studs having smooth faced shanks shaped to snugly fit the apertures in said support and being adapted to be inserted in said apertures as a force fit, and an electrical conductor secured to said studs.
- 25 2. In a device of the kind described, a support of insulating material having a series of smooth-walled apertures formed therein, a series of studs also of insulating material having smooth faced shanks shaped to snugly fit the apertures in said support and being adapted to be inserted by a driving fit in said apertures, and an electrical conductor secured to said studs.
- 30 3. In a device of the class described, a support of insulating material having a series of smooth-walled apertures formed therein, a series of studs also of insulating material having shanks adapted to be secured by a driving fit into said insulating support, and an electrical conductor secured to said studs.
- 35 4. In a device of the class described, a support of insulating material having a series of smooth-walled apertures formed therein, a series of studs also of insulating

material having substantially cylindrical shanks secured in the apertures in said support by a driving fit, said studs each having a transverse kerf in the upper portion thereof, an electrical conductor seated in the kerfs in said studs and transversely extending pins secured in said studs for holding the conductor in place.

5. In a device of the kind described, a skeleton frame of insulating material provided with a series of radially extending rods having smooth-walled cavities formed therein, studs of insulating material having smooth shanks adapted to be secured by a driving fit in the apertures in said rods, each of said studs having an enlarged upper portion with a kerf formed therein, an electrical conductor seated in the kerfs in said studs and means extending transversely through said studs to securely hold said conductor in the kerfs in said studs substantially as set forth.

6. In a device of the kind described, a conductor support of insulating material having a series of smooth-walled apertures formed therein; a series of studs having smooth faced shanks shaped to snugly fit the apertures in said support, and being adapted to be inserted in said apertures as a force fit.

7. In a device of the kind described, a conductor support of insulating material having a series of smooth-walled apertures formed therein, a series of studs also of insulating material having smooth faced shanks to snugly fit the apertures in said support and being adapted to be inserted by a driving fit in said apertures.

In witness whereof we have hereunto set our hands at the borough of Manhattan, city and State of New York, this third day of November, 1917.

LOUIS STEINBERGER.
GUY HILL.

In presence of—

ZITA M. GRAHAM,
ISABEL R. RICHARDS.
